UNITED STATES PATENT OFFICE.

FERDINANDO DE GRAZIA, OF WASHINGTON, DISTRICT OF COLUMBIA.

SAFETY-RAZOR.

1,400,031.

Specification of Letters Patent. Patented Dec. 13, 1921.

Application filed May 20, 1920. Serial No. 382,953.

To all whom it may concern:

Be it known that I, FERDINANDO DE GRAZIA, a citizen of Italy, residing at Washington, in the District of Columbia, have 5 invented certain new and useful Improvements in Safety-Razors, of which the following is a specification.

This invention relates to certain new and useful improvements in safety razors and 10 has for its primary object to provide in a safety razor of the Gillette type, a substitute guard plate having a guard roller removably journaled at each edge thereof in proximity of the cutting edge of the blade to protect 15 the cutting edge of the blade.

A further object of the invention resides in the provision of a guard plate for safety razors wherein a guard roller is removably journaled adjacent each side edge of the 20 guard plate to protect the cutting edge of the blade and to be substituted for the usual form of guard plate having a serrated toothed edge.

With the above and other objects in view, 25 the invention consists in the novel form, combination and arrangement of parts hereinafter more fully described and shown in the accompanying drawing, wherein like reference characters designate similar parts 30 throughout the several views.

In the drawing,

Figure 1 is a perspective view of a safety razor constructed in accordance with the present invention, showing the guard rollers 35 removably journaled in the opposite sides of the guard plate,

Fig. 2 is a vertical transverse sectional view of the razor, with the handle partially broken away,

Fig. 3 is an end elevational view of the device with the handle partially broken away and with the guard rollers shown in dotted lines as removed from the guard plate.

Fig. 4 is a cross sectional view taken on 45 line IV—IV showing the resilient gripping fingers carried by the end flanges of the guard plate for revolvably supporting the guard rollers,

Fig. 5 is a detached perspective view of 50 the improved guard plate, and

Fig. 6 is a perspective view of one of the guard rollers removed from the guard plate.

The present invention has for its primary object to provide a substitute guard plate 55 for the type of safety razor known as the

"Gillette" and embodies guard rollers removably journaled at each side of the guard plate to function in lieu of the guard teeth upon the plate of the safety razor referred to. The guard rollers are carried by the side edges of the guard plate slightly in advance of the cutting edge of the razor blade, and protect the cutting edge of the blade and further present the entire surface to be shaved to the cutting edge of the blade. In 60 devices of this character where guard teeth are employed, the razor in cutting only presents spaced portions of its cutting edge for a cutting operation due to a contact of the cutting edge of the razor blade with the 65 guard teeth and it is necessary to direct the cutting movement of the razor in many directions to assure a complete shaving operation. The guard plate has uninterrupted 70 opposite edges and is formed on a transverse 75 arc coincident with the inner curved face of the clamping plate while end flanges carried by the guard plate have the opposite ends thereof bifurcated to form resilient 75 fingers for engaging and revolvably supporting the guard rollers.

Referring more in detail to the accompanying drawing and particularly to Figs. 1, 2, and 4, there is illustrated a safety razor embodying a clamping plate 7 of elongated 80 form and transversely curved and tapered at the opposite edges thereof as illustrated. A screw plug 8 centrally projects from the inner curved face of the plate 7 for engagement in the threaded socketed end 9 of the 85 handle 10. The type of razor blade employed with this holder and clamping plate includes a single opening for the passage of the screw plug 8 and oppositely positioned 90 openings for the passage of the guide fingers 95 11 extending in alignment with the screw plug 8.

The guard plate employed in this safety razor embodies a plate section 12 transversely curved coincident to the curvature 100 of the clamping plate 7 and having three aligned openings 13 arranged centrally and longitudinally thereof for reception of the guide pins 11 and the screw plug 8 as shown in Figs. 2 and 5. The guard plate 12 is 105 coextensive with the clamping plate 7 and is provided upon each end thereof with an inwardly directed flange 14, of slightly increased breadth at the opposite ends thereof with the ends of the flanges 14 bifurcated 110

as at 15 to form resilient gripping fingers, the end flanges 14 projecting laterally of the guard plate 12 as shown in Fig. 5. A guard roller is removably journaled in each side of the guard plate 12 and embodies a cylindrical body portion 16 having a reduced bearing 17 at each end thereof. The roller bearings 17 are positioned between the resilient fingers formed by the bifurcation 15 and are retained in opposed curved recesses 15' formed in the resilient fingers, the rollers being permitted freely to revolve within their bearings and prevented from accidental displacement by the resiliency of 10 the fingers. When so positioned, the guard rollers 16 project beyond the opposite edges of the guard plate 12 and in position to protect the cutting edge of a razor blade. 15

In assembling the different parts of the 20 razor, assuming that the handle 10 is detached from the screw plug 8 of the clamping plate, a razor blade 18 having three aligned openings therein is placed upon the clamping plate with the fingers 11 projecting 25 through the end openings and the screw plug 8 projecting through the central opening thereof. The guard plate is then positioned upon the clamping plate and in engagement with the blade 18. The socketed 30 end 9 of the handle 10 receives the screw plug 8 and by screwing the handle upon the plug, the end 9 of the handle engages the inner face of the guard plate 12, and said blade 18 being flexible, the same is curved 35 by the guard plate 12 moving into proximity of the clamping plate 7 to be tensioned between the two plates and locked therebetween by the screw handle 10. When so arranged, the opposite cutting edges 18' of the 40 blade 18 are positioned inwardly of the guard rollers 16 as shown in Figs. 1, 3, and 4 to be protected by the rollers and also sufficiently spaced therefrom to present the entire cutting edge of the blade for operation. 45 In using the device, the guard roller 16 rolls over the surface to be shaved and presents the entire surface contacted by the roller to the cutting edge of the blade. In this manner, the entire cutting edge of the 50 blade is subjected to operation as distinguished from the alternate cutting portions of a blade that is protected by a toothed guard plate. In cleaning the device, the sev-

eral parts are separated by unscrewing the handle 10 and the guard rollers 16 are readily removable from the guard plate 12 by forcing the same from the open outer ends of the resilient fingers carried by the end flanges. If desired, the bearing ends 17 of the roller 16 may project a sufficient distance 55 beyond each end of the guard plate 12 to facilitate gripping of the roller bearings during removal of the roller from the guard plate. Also, knobs or heads may be formed 60 on the ends of the bearings for grasping 65 during removal.

It is intended to construct the complete safety razor in accordance with the invention as above outlined, and also to manufacture the guard plate alone as a substitute 70 for the form of toothed guard plate in the safety razor referred to. While there is herein shown and described the preferred embodiment of the invention, it is nevertheless to be understood that minor changes 75 may be made therein, without departing from the spirit and scope of the invention as hereinafter claimed.

What is claimed as new is:

1. In a safety razor wherein a guard 80 plate is transversely curved, spring fingers carried by the opposite ends of the plate, and guard rollers removably journaled in said fingers and retained in operative position on said plate by the resiliency of the 85 spring fingers.

2. In a safety razor wherein a guard plate is transversely curved and is provided with end flanges extending laterally of the plate, spaced resilient fingers formed on the extensions of the end flanges, and guard rollers removably journaled in the resilient fingers and retained in operative position on said plate by the resiliency of said fingers. 90

3. In a safety razor of the type described, 95 wherein a guard plate and clamping plate engage a razor blade, with guard rollers removably journaled on said guard plate, said guard plate being constructed to resiliently maintain the guard rollers in operative position thereon and to permit removal of the guard rollers by forceful extraction against the resilient retaining means therefor. 100

In testimony whereof I affix my signature.

FERDINANDO DE GRAZIA.
